[57] CLAIM

The ornamental design for a chair or similar article, substantially as shown and described.

DESCRIPTION

FIG. 1 is a perspective front view of a chair or similar article embodying my new design.

FIG. 2 is a side elevational view of the chair or similar article of FIG. 1;

FIG. 3 is a perspective back view of the chair or similar article of FIGS. 1 and 2; and

FIG. 4 is a top plan view of the chair or similar article of FIGS. 1 through 3.

The essential features of my design reside solely in the upper portion comprised of the armrests, seat and back member, all as best illustrated in FIGS. 2, 3 and 4.
